UNITED STATES PATENT OFFICE

JAMES F. KAVANAGH, OF CLIFFSIDE, NEW JERSEY, ASSIGNOR TO THE SUPERHEATER COMPANY, OF NEW YORK, N. Y.

STEAM GENERATOR

Application filed March 12, 1930. Serial No. 435,134.

My invention relates to the art of generating steam and aims to provide a boiler of low draft loss and so arranged that a superheater may be installed therein conveniently and at relatively low cost.

The novel features of the present invention will be pointed out in the appended claims. The invention itself, however, together with further objects and advantages, 10 will best be understood from a detailed description of a steam generating system in accordance with my invention, and such a description will now be given of a particular embodiment of the invention illustrated in 15 the accompanying drawings in which

Fig. 1 is a vertical longitudinal section of a transverse drum water tube boiler having a superheater and furnace associated therewith;

20 Fig. 2 is a fragmentary elevation of the front of the boiler and superheater illustrated in Fig. 1; and

Fig. 3 is a fragmentary section on the line 3—3 of Fig. 1 looking in the direction of the 25 arrows.

The boiler and superheater installation illustrated in the drawings comprises a furnace chamber 10 above which is a tube bank 12 designed to act as a slag screen and composed of straight tubes inclined to the horizontal and running from a rear header 14 upwardly to a front header 16. When the bank 12 is heated, a thermal circulation through 30 the tubes of bank 12 is produced in the direction indicated by the arrows on Fig. 1. Means for producing such circulation is illustrated as comprising a steam and water drum 18 from which extend downwardly

35 downcomer nipples 20 below which are vertical headers 22, the purpose of which will presently appear. Water flowing downwardly through nipples 20 and headers 22 passes into nipples 24 which connect into the

40 lower ends of headers 22 and conduct water downwardly into the tops of headers 14 from which it passes into bank 12. After passing through the tube bank 12, water, and the steam formed therein, is returned to drum 18 through two sets of circulator nipples and

45 headers. One of said sets of return circula- 50

tors comprises nipples 26 which connect with the tops of alternate headers 16 and run upwardly to the roof of the boiler at which point they are curved horizontally toward drum 18 and extend back above the forward ends of 55 the tubes 12 to horizontal headers 28. Water and steam which have been delivered to the headers 28 by nipples 26 are delivered to the drum 18 by nipples 30. Intermediate the nipples 26 is a set of shorter nipples 26a which connect the tops of alternate headers 16 into the bottoms of vertical headers 32. Water, and the steam therein, which has passed through headers 32 is delivered to the drum 18 by nipples 30a which run from the tops of 60 the headers 32 up to the level of the boiler roof at which point they curve and run horizontally to the drum 18 passing between the horizontal headers 28.

Connected between alternate headers 22 and the headers 32 is a group or bank of horizontally inclined straight tubes 34 and connected between alternate vertical headers 22 and the horizontal roof headers 28 is a group of bent tubes 36. Tubes in bank 34 65 and in bank 36 are arranged in vertical rows and those in bank 34 maintain the usual inclination throughout their length. Tubes 36 are parallel to tubes 34 for approximately half their lengths and then curve upward 70 sharply so as to run substantially vertical at their upper ends. It will be seen that the thermal circulation through tubes 34 comprises the drum 18, nipples 20, headers 22, 75 headers 32, and tubes 30a, whereas the thermal circulation through tubes 36 comprises the drum 18, nipples 20, headers 22, headers 28, and nipples 30.

As the upper ends of tubes 36 are curved 80 sharply upwardly, the space otherwise occupied by these tubes at the forward end of the boiler is left vacant and advantage of this is taken to install superheater elements 38, 38 in such space. As shown, the elements 38 are connected between headers 40 and 42 85 which lie above the boiler roof, the ends of the elements 38 extending down between the horizontal portion of the nipples 26 and 30a and being looped back and forth in vertical 90 planes so as to extend down between the rows 95

of tubes 34. As appears from Fig. 3, four superheater elements may be placed in the space between each pair of vertical rows of tubes 34. Preferably the elements extend 5 downwardly to or slightly below the lower edge of the tube bank 34 so that their lower ends may contact with high temperature gases which have just passed through the slag screen 12. Elements 38 are, however, protected against overheating when starting up 10 the boiler due to the fact that they are interspersed between water tubes 34.

For controlling the flow of gases from furnace 10 to best advantage, I have illustrated 15 baffling comprising a baffle 44 running from the headers 14 along the upper edge of the tube bank 12 for approximately half the length of tubes 12 at which point it connects with a baffle 46 running upwardly and somewhat 20 forwardly across the tubes 34 and adjacent the forward edge of the tube bank 36. Gases may pass through upwardly between the baffle 46 and the front of the boiler and thence across the upper ends of the tubes 36, 25 a baffle 48 being provided which depends from the roof of the boiler intermediate the headers 28 and drum 18 to direct the gases downwardly across tubes 34 and 36 and thence 30 upwardly between the baffle 48 and the rear of the boiler to the uptake 50.

It will be seen that the path of the gases as above described is similar to that of the standard type of boiler but the draft loss is less in my boiler than in the standard type 35 since the space between the tubes is greater during a portion of the course of the gases. Also, the superheater elements occupy space which is ordinarily taken by boiler tubes so that there is no separate draft loss chargeable 40 to the superheater as such.

It will be understood that in the ordinary cross drum straight tube type of boiler the superheater is ordinarily placed in the interdeck space between two banks of tubes. Such 45 an arrangement adds to the height of the boiler so that the arrangement herein disclosed enables a superheater boiler of approximately standard type to be installed with less than the usual height. Furthermore, the 50 supports for the superheater are lower in cost compared to the interdeck type of installation while the usual special interdeck cast iron baffle section is eliminated.

I claim:

- 55 1. The combination in a boiler of a bank of water tubes arranged in vertical rows and curved sharply upward at one end, a second bank of water tubes also arranged in vertical rows and having its rows intermediate those 60 of said first bank for a portion of their length, said second bank projecting beyond the upturned ends of said curved bank at one end of the boiler, and means for causing thermal circulation through said banks when heated.
- 65 2. The combination as set forth in claim 1

together with a slag screen bank below the other banks and means for causing a thermal circulation through the slag screen bank when heated.

3. The combination as set forth in claim 1 70 together with superheater elements intermediate the rows of the projecting bank, and baffling for directing furnace gases upward over said superheater and then through the 75 upturned ends of the curved bank.

4. The combination as set forth in claim 1 together with a slag screen bank lying below the other two banks, means for causing a thermal circulation through said slag 80 screen when heated, a superheater having 80 elements lying above said slag screen bank and intermediate the rows of the projecting bank, and baffling for directing gases upwardly through said slag screen and said superheater elements and then through the 85 upper ends of said curved bank.

5. A boiler having sets of vertical and a set of horizontal headers, a group of generating tubes in vertical rows and connecting said horizontal headers to one set of said vertical 90 headers, a group of generating tubes in vertical rows intermediate those of said first group and projecting beyond the tubes of said first group at one end and connected to vertical headers at both ends, a slag screen 95 bank below said groups and of the same length as said second group and connected to vertical headers, a steam and water drum, nipples connecting the vertical headers at one end of both said groups direct to said 100 drum, nipples connecting said same end of both groups to the headers of said slag screen bank, nipples connecting headers at the other end of said slag bank, some to said horizontal headers and some to vertical headers 105 of said second group, nipples connecting said horizontal headers to said drum, and members connecting the remaining vertical headers of said second group to said drum.

6. The boiler set forth in claim 5 together 110 with a superheater having elements intermediate the rows of the second group of tubes and above the slag screen bank.
